Thomas J. Donnelly
ATTORNEY.

UNITED STATES PATENT OFFICE.

GEORGE P. KAUL, OF DETROIT, MICHIGAN.

BATHING CAP.

Application filed August 5, 1926. Serial No. 127,683.

My invention relates to a new and useful improvement in a bathing cap in which the crown of the cap is made from waterproof material. The custom among swimmers today is to swim in the water for a portion of the time and loll on the beaches for a portion of the time.

The bathing caps as now manufactured fit snugly around the head so as to prevent the hair becoming wet but afford no protection for the eyes and face against the downwardly directed rays of the sun.

It is an object of the present invention to provide a bathing hat having a peak or shield which may be moved to operative or inoperative position at will so that it is not in a position to interfere with the vision of the swimmer while swimming, and so arranged that it may be moved to shielding or operative position on the wearer when not engaged in swimming.

It is another object of the present invention to provide a peak mounted on a waterproof crown in such a way that the movement of the peak from operative to inoperative position will not wear or tear the crown at its point of connection.

Another object of the invention is to provide a reinforcement for the crown at the point of mounting the peak so that the device is durable and also sets comfortable on the head.

Other objects will appear hereinafter.

The invention consists in the combination and arrangement of parts hereinafter described and claimed.

The invention will be best understood by a reference to the accompanying drawings which form a part of this specification and in which,

Fig. 1 is a side elevational view showing the invention applied.

Fig. 2 is a fragmentary front elevational view of the invention.

Fig. 3 is a fragmentary sectional view taken on substantially line 3—3 of Fig. 2.

The invention is adapted for use with a crown forming portion 7 which is made from rubber or other suitable waterproof material. Mounted on the forward end of the crown portion 7 at its edge on the inner surface thereof is a strip of reinforcement 8 which may be made from cloth, leatheroid, or other suitable material, which will be flexible and

at the same time stiffen to a certain extent 55 this portion of the crown 7. A similar layer of reinforcement 9 is secured to the outer side of the crown 7 in registration with the strip 8. The peak 10 is provided with a strip of reinforcement 11 along its outer edge and a strip of reinforcement 12 at its joined edge. The peak may be made from any suitable material although I prefer to use celluloid which may be obtained in various colors.

As shown in full lines in Fig. 1 the peak 10 may be folded downwardly to form a shield or protective member for the face and eyes. The peak or shield would be worn in this position when the wearer is not 70 swimming. When it is desired to swim so that the vision of the wearer may be unobstructed entirely the peak may be folded upwardly into the position shown in dotted lines in Fig. 1, this folding taking place on 75 the line of stitching 13 which secures the peak to the crown 7, this stitching being projected through the reinforcing members 8 and 9 and 12. The stitching 14 is used to 80 secure the reinforcing members 8 and 9 at their upper edges and at their end edges to the crown 7. In view of the fact that the stitching 13 is positioned slightly above the lower edges of the strips 8 and 9, the strip 8 will not be folded when the peak is turned 85 to inoperative position as shown in dotted lines in Fig. 1, so that no pressure along the single line will be exerted upon the forehead of the wearer to any great extent. On 90 this account the bathing cap is as comfortable on the head of the wearer when the peak is in inoperative position as when the peak is in operative position. Furthermore on account of the reinforcement no noticeable or undue wear is had on the cap in the point 95 of connection on account of the movement of the peak from operative or inoperative position.

The peak when positioned to inoperative position crosses center and the yieldable 100 crown 7 serves to retain the peak in either position, this action resulting from the elasticity of the material from which the crown 7 is made.

A bathing cap constructed in this manner 105 is not only ornamental and attractive but possessed of considerable utility over the peakless bathing cap for the reasons set out.

While I have illustrated and described the preferred form of structure, I do not wish to limit myself to the precise form of structure shown, but desire to avail myself of such variations and modifications as may come within the scope of the appended claims.

Having thus described my invention what I claim as new and desire to secure by Letters Patent is:

1. A bathing cap of the class described, comprising: an elastic water-proof crown forming member; a reinforcement mounted on said crown at its forward side adjacent its edge; a flexible peak of comparatively stiff material secured to said reinforcement inwardly of the edge thereof and adapted

for tilting to operative or inoperative position.

2. A bathing cap of the class described, comprising: an elastic water-proof crown; a reinforcement member secured to the inner surface of said crown at its forward side adjacent its edge; a reinforcement member secured to the outer surface of said crown at its forward side adjacent said edge; a flexible peak of comparatively stiff material secured to said reinforcement members inwardly of the edges thereof, said peak being tilttable to operative or inoperative position.

In testimony whereof I have signed the foregoing.

GEORGE P. KAUL.
